Fig. 9.

Fig. 10.

Fig. 11.

FIG. 14.

FIG. 15.

FIG. 16.

FIG. 1 is a front top perspective view of a furniture seat showing our new design.

FIG. 2 is a rear top perspective view thereof.

FIG. 3 is a front top perspective view of a modified form of the furniture seat shown in FIG. 1.

FIG. 4 is a rear top perspective view of the furniture seat of FIG. 3.

FIG. 5 is an end elevational view of the furniture seat of FIG. 3.

FIG. 6 is a front top perspective view of another modified form of the furniture seat of FIG. 1.

FIG. 7 is a rear top perspective view of the furniture seat of FIG. 6.

FIG. 8 is an end elevational view of the furniture seat of FIG. 6.

FIG. 9 is a front top perspective view of another modified form of the furniture seat shown in FIG. 1.

FIG. 10 is a rear top perspective view of the furniture seat of FIG. 9.

FIG. 11 is an end elevational view of the furniture seat of FIG. 9.

FIG. 12 is a front top perspective view of another modified form of the furniture seat shown in FIG. 1.

FIG. 13 is a rear top perspective view of the furniture seat of FIG. 12.

FIG. 14 is a front top perspective of another modified form of the furniture seat shown in FIG. 1.

FIG. 15 is a rear top perspective of the furniture seat of FIG. 14.

FIG. 16 is an end elevational view of the furniture seat of FIG. 14.

This application is a continuation-in-part of our design application Ser. No. D. 19,872, filed Oct. 31, 1969, for Slat Furniture.

We claim:

The ornamental design for a furniture seat, substantially as shown.
